ZONE AIR CONDITIONING SYSTEM

Arthur C. Grant, St. Paul, Minn., assignor to
Minneapolis-Honeywell Regulator Company,
Minneapolis, Minn., a corporation of Delaware

Application December 31, 1934, Serial No. 759,918

11 Claims. (Cl. 236—1)

This invention relates to zone air conditioning systems for use in buildings where it is desirable to differently condition various rooms or groups of rooms.

In conditioning buildings and especially in houses it is desirable to have certain rooms such as the living room, dining room and library maintained at a certain temperature and relative humidity while it is desirable to have other rooms such as bedrooms and servants' quarters maintained at another temperature. This is also true for summer cooling as well as for winter heating.

It is therefore an object of this invention to provide a novel zone air conditioning system whereby certain rooms of a building are maintained at one condition and the other rooms at another condition.

Another object of this invention is to provide a novel zone air conditioning system wherein certain rooms of a building are conditioned by means of an air conditioning unit and other rooms are conditioned by direct radiation.

A further object is to provide an automatic zone air conditioning system for winter heating and for summer cooling whereby various rooms of a building are maintained at different conditions and wherein the conditioning system may be readily changed from winter heating to summer cooling operation.

Another object is to provide a zone air conditioning system having an air conditioning unit for certain rooms of a building and direct radiation means for other rooms wherein the air conditioning unit and the direct radiation means are independently controlled and wherein a common circulating means is used to circulate conditioning fluid through the air conditioning unit and the direct radiation means.

Other objects and advantages will become apparent to those skilled in the art by reference to the accompanying specification, claims and drawing in which drawing there is diagrammatically shown the zone air conditioning system of this invention.

The invention is shown and described as a conditioning system for four rooms A, B, C and D. Rooms C and D which are the rooms mostly used, such as a living room, dining room and study in a domestic building are heated or cooled and humidified by means of an air conditioning unit. The rooms A and B which are remote and not used as often as the rooms C and D such as bedrooms and servants' quarters are heated or cooled by direct radiation. The term "direct

radiation" is used to distinguish conditioning by radiators from conditioning by an air conditioning unit. Various types of radiators, such as exposed, enclosed or shielded, may be used for conditioning and the manner of conditioning caused thereby is termed for purposes of illustration as direct radiation.

Although heat may be obtained from any source, for purposes of illustration, the heat is generated in a hot water boiler 10 which may be gas-fired, the gas entering the boiler 10 from some source not shown through a pipe 12. Located in the pipe 12 is a gas control valve 11 for controlling the supply of gas to the boiler 10. The gas valve is moved to open position by energizing a solenoid or motor mechanism 13 and upon deenergization thereof the valve 11 is closed. Located on the boiler 10 in such a manner as to respond to changes in temperature in the boiler is a conventional boiler thermostat 14 which is secured in place by means of a binding post 17. The thermostat 14 carries a contact 15 which is moved into engagement with a stationary contact 16 when the boiler temperature drops below a predetermined value and which is moved out of engagement with the contact 16 when the boiler temperature rises above the predetermined value. Wires 18 and 19 lead from some source of power, not shown, the wire 18 being connected to a manually controlled switch 20 arm 20 and the wire 19 being connected to the solenoid or motor mechanism 13. The manually operated switch arm 20 is adapted to engage a contact 21 which is connected by means of a wire 22 to the binding post 17 of the thermostat 14. The stationary contact 16 is connected by means of a wire 23 to the solenoid or motor mechanism 13.

When the control means for the boiler 10 is to be placed in operation for winter heating, the switch arm 20 is moved into engagement with the contact 21. When the temperature of the boiler 10 is below a predetermined value, contact 15 engages contact 16 to complete a circuit from wire 18, switch arm 20, contact 21, wire 22, binding post 17, thermostat 14, contact 15, contact 16, wire 23 and solenoid 13 to wire 19 to energize the solenoid 13 to open the valve 11 to admit gas to the boiler 10 to raise the temperature of the boiler 10. When the temperature of the boiler 10 reaches the predetermined value, the thermostat 14 moves the contact 15 out of engagement with the contact 16 to break the above circuit to deenergize the solenoid 13 to close the valve 11 to stop firing of the boiler. In

this manner, the heating fluid in the boiler 10 is maintained at a constant temperature.

Connected to the top of boiler 10 is a hot water supply pipe 25, having a manually operated shut-off valve 26 located therein. The supply pipe 25 is connected to a four-way connection 21. Also, connected to the four-way connection 21 is a pipe 28 having a control valve 29 located therein, said control valve 29 being moved to open or closed positions by means of a reversible electric motor 24 having the usual limitswitches contained therein. The pipe 28 connects to a pipe 30 and risers 31 extend upwardly therefrom and are connected to radiators 32 located in rooms A and B. Return risers 33 extend downwardly from the radiators 32 located in rooms A and B and connect into a pipe 34 which contains a four-way connection 35. A circulating pump designated at 37 is operated by an electric motor 44 and a pipe 36 connects the four-way connection 35 to the circulating pump 37. A pipe 38 connects the circulating pump 37 with the boiler 10 to return water from the radiators 32 to the boiler 10 to be reheated therein. Located in the pipe 38 is a manually controlled shut-off valve 39. When the manually controlled shut-off valves 26 and 39 and the control valve 29 are opened and the circulating pump 37 is placed in operation, hot water will be circulated from the boiler 10 through the radiators 32 to cause heating of the rooms A and B by direct radiation.

Connected to the four-way connection 21 is a pipe 40 leading from some source of cooling medium and a manually controlled shut-off valve 41 is located in this pipe 40. Connected to the pipe 38 between the circulating pump 37 and the shut-off valve 39 is a pipe 42 leading to the source of cooling medium and having located therein a manually controlled shut-off valve 43. The cooling medium supplied to the pipe 40 may emanate from any known source such as a mechanical refrigeration system, an ice cooling system or a city water supply system. By closing the manual shut-off valves 26 and 39 and by opening the manually operated shut-off valves 41 and 43, cooling fluid is supplied to the system for summer cooling instead of heating fluid from the boiler 10. With the shut-off valves in the positions just described, and if the valve 29 is opened and the circulating pump 37 is put in operation, cooling fluid will be circulated through the radiators 32 in the rooms A and B to cool the same by means of direct radiation. From the above, it is seen that the radiators 32 may either heat or cool the rooms A and B by direct radiation, depending upon whether the rooms should be heated or cooled by manually manipulating the manually controlled shut-off valves 26, 39, 41 and 42.

An air conditioning unit of any known type, having a heat exchanger 46 located therein is designated at 45. The heat exchanger 46 is connected by means of a pipe 47 to the four-way connection 21 and by means of a pipe 48 to the four-way connection 35. When the circulating pump 37 is put in operation, heating fluid or cooling fluid is circulated through the heat exchanger 46 depending upon the positions of the shut-off valves 26, 39, 41 and 43. Air is passed over the heat exchanger 46 by means of a fan 49 driven by an electric motor 51 by means of a belt 50. The air is drawn through filters 52 and passed over the heat exchanger 46 and is conducted by means of ducts 53 through registers 54 into the rooms C and D. Located above the heat exchanger 46 in the air conditioning unit 45 is a humidifying

device of any known type illustrated as a spray device 55, which is supplied with water through a pipe 58 from some source not shown. The supply of water to the humidifying spray device 55 is controlled by means of a valve 56 which is opened by energizing a solenoid or motor device 57 connected thereto and which is closed by de-energizing the solenoid 57.

From the above, it is seen that heated or cooled air is supplied to the rooms C and D, depending upon whether the rooms C or D should be heated or cooled and also that the humidity of the air so supplied is controlled by means of the humidifying spray device 55.

Located in the room A is a room thermostat 60 which is mounted for operation on a binding post 61. The thermostat 60 carries a contact 62 which is selectively moved into and out of engagement with contacts 63 and 64. Contacts 63 and 64 are connected by means of wires 69 and 70 respectively to switch arms 65 and 66 respectively of a double throw, double-poled reversing switch. The switch arms 65 and 66 when moved to the right are adapted to engage respectively the contacts 67 and 68 and when moved to the left are adapted to engage respectively the contacts 68' and 67'. 71 and 72 are line wires that lead from some source of power not shown and which are connected to opposite ends of a primary 73 of a step-down transformer 74. One end of the secondary 75 of the step-down transformer 74 is connected by means of a wire 76 to the binding post 61 of the thermostat 60. The other end of the secondary 75 is connected by means of a wire 77 to the electric motor 24. The contacts 67 and 68 of the reversing switch are also connected by means of wires 78 and 79 respectively to the electric motor 24.

Assume that the valve 29 is held in a closed position by means of the electric motor 24, that the switch arms 65 and 66 of the reversing switch are in engagement with the contacts 67 and 68 and that the system is conditioned for winter heating operation. When the room thermostat 60 calls for heat, the contact 62 thereof is moved into engagement with the contact 63 thereby completing a valve opening circuit from the secondary 75 of the step-down transformer 74 through wire 76, binding post 61, thermostat 60, contacts 62 and 63, wire 69, switch arm 65, contact 67, wire 79, electric motor 24 and wire 77 back to the secondary 75 of the step down transformer 74. Upon completion of this circuit, the electric motor 24 is operated in one direction to open the control valve 29 to permit circulation of the heating fluid through the radiators 32 of rooms A and B to heat these rooms A and B by means of direct radiation. When room A has become sufficiently heated, the thermostat 60 moves the contact 62 thereof into engagement with the contact 64, thereby completing a valve closing circuit from the secondary 75 of step-down transformer 74 through wire 76, binding post 61, thermostat 60, contacts 62 and 64, wire 70, switch arm 66, contact 68, wire 78, electric motor 24, and wire 77 back to the secondary 75 of the step down transformer 74. Upon completion of this circuit, the electric motor 24 is operated in the reverse direction to move the valve 29 to a closed position to stop circulation of the heating fluid through the radiators 32.

Assume now that the shut-off valves 26, 39, 41 and 43 are positioned for summer cooling operation, that the reversing switch has also been positioned for summer operation by caus-

ing engagement of switch arms 65 and 66 with contacts 68' and 67' respectively, that control valve 29 is in a closed position and that the temperature of the room A rises above a predetermined value. Upon such rise in temperature, thermostat 60 moves the contact 62 into engagement with contact 64 to complete a circuit from secondary 75 of the step-down transformer 74 through wire 76, binding post 61, thermostat 60, contacts 62 and 64, wire 70, switch arm 66, contact 67', wire 79, electric motor 24 and wire 77 back to the secondary 75 of the step-down transformer 74. Upon completion of this circuit, the electric motor 24 is moved in one direction to move the valve 29 to open position to permit circulation of the cooling medium through the radiators 32 to cool the rooms A and B by direct radiation. When the temperature of the room A has fallen below a predetermined value, thermostat 60 moves the contact 62 into engagement with the contact 63 to complete a circuit from the secondary 75 of step-down transformer 74 through wire 76, binding post 61, thermostat 60, contacts 62 and 63, wire 69, switch arm 65, contact 68', wire 78, electric motor 24, and wire 77 back to the secondary 75. The completion of this circuit causes reverse energization of motor 24 to move the valve 29 into closed position to stop circulation of the cooling fluid to the radiators 32.

Electric motor 24 also operates a lever 81 which carries a mercury switch 82 of the usual type having a pair of electrodes located therein which are contacted by means of the usual mercury upon the tilting of the mercury switch 82 to a given position. When the valve 29 is closed, the arm 81 is in the down position as shown in the drawing and the mercury in the mercury switch 82 is out of engagement with the electrodes of mercury switch 82. In other words, when the valve 29 is closed, the mercury switch 82 is in open circuit position. When the valve 29 is moved to open position by the electric motor 24, the lever 81 is moved upwardly to tilt the mercury switch 82 into circuit closing position.

Leading from some source of power not shown are line wires 83 and 84. One of the electrodes of the mercury switch 82 is connected by means of a wire 85 to the line wire 83. The other electrode of mercury switch 82 is connected by means of wires 86 and 87 to the electric motor 44 which drives the circulating pump 37. The electric motor 44 is in turn connected by means of wires 88 and 89 to the line wire 84.

When the valve 29 is moved to an open position, the mercury tube 82 is tilted to cause the mercury contained therein to engage the electrodes thereof to complete a circuit from the line wire 83 through wire 85, mercury switch 82, wire 86, wire 87, electric motor 44, wire 88 and wire 89 back to the line wire 84. Upon completion of this circuit, the electric motor 44 is energized to cause operation of the circulating pump 37. When the control valve 29 is moved to a closed position by the electric motor 24, the mercury switch 82 is tilted to the open circuit position thereby breaking the above mentioned circuit to stop operation of the electric motor 44 to stop operation of the circulating pump 37.

From the above, it is seen that when the system is set for winter operation in the manner described and when the room thermostat 60 calls for heat, the control valve 29 is opened and the motor 44 is energized to operate the circulating pump 37 to cause circulation of the heating

fluid from the boiler 10 through the radiators 32 to cause heating of the rooms A and B by direct radiation and that when the temperature of the room rises above a predetermined value, the control valve 29 is closed and the circulating pump 37 is stopped to prevent circulation of the heating fluid through the radiators 32. It is also seen that when the structure as set out above is set for summer operation, that is for cooling, and when the temperature of the room rises above a predetermined value, the control valve 29 is opened and the circulating pump 37 is operated to cause circulation of the cooling fluid to the radiators 32 to cool the rooms A and B by direct radiation and that when the temperature in the room lowers below a predetermined value, the control valve 29 is closed and the circulating pump 37 is stopped to prevent circulation of the cooling fluid through the radiators 32.

Located in the room C is a room thermostat 91 supported for operation on a binding post 92. The room thermostat 91 selectively moves a contact 93 into engagement with either contact 94 or contact 95. Contact 94 is connected by means of a wire 96 to a switch arm 98 of a reversing switch and contact 95 is connected by means of a wire 97 to a switch arm 99 of the reversing switch. The switch arms 98 and 99 of the reversing switch are moved selectively into engagement with contacts 100 and 101 or contacts 101' and 100' respectively.

A double coil relay comprises an energizing coil 102 and a bucking or neutralizing coil 103. The relay is operatively connected to switch arms 104, 105 and 106 to move these switch arms into engagement with contacts 107, 108 and 109 respectively upon energization of the energizing coil 102. The switch arms 104, 105 and 106 are normally held out of engagement with the contacts 107, 108 and 109 by a biasing means such as gravity, springs or other means not shown. Upon energization of the energizing coil 102, the switch arms are moved into engagement with their respective contacts against the bias of the opening means and upon energization of the neutralizing coil 103 or bucking coil 103 which neutralizes the pulling effect of the energizing coil 102, the switch arms are moved out of engagement with their respective contacts by the biasing means which tends to maintain the switches in open position.

Line wires leading from some source of power not shown are designated at 110 and 111 and these wires are connected to opposite ends of a primary 112 of a step-down transformer 113. The step down transformer 113 is provided with a secondary 114 one end of which is connected by means of a wire 115 to one end of the energizing coil 102. A wire 116 also connects the same end of the energizing coil 102 with one end of the bucking or neutralizing coil 103. The other end of the neutralizing coil 103 is connected by means of a wire 117 to the contact 101 of the reversing switch. The contact 100 of the reversing switch is connected by means of a wire 118 and a wire 119 to the other end of the secondary 114 of the step-down transformer 113. The other end of the energizing coil 102 is connected by means of a wire 120 to the binding post 92 of the room thermostat 91. The switch arm 104 is connected to the connection between wires 118 and 119 by means of a wire 121 and the contact 107 which cooperates with the switch arm 104 is connected to the connection between the wire 120 and the energizing coil 102.

Assume that the device is to be used for win-

ter heating and that switch arms 98 and 99 are moved into engagement with contacts 100 and 101. Upon a call for heat by the thermostat 91, the contact 93 is moved into engagement with the contact 94 thereby completing a circuit from the secondary 114 of step-down transformer 113 through wire 119, wire 118, contact 100, switch arm 98, wire 96, contacts 94 and 93, thermostat 91, binding post 92, wire 120, energizing coil 102 and wire 115 back to the secondary 114. Upon completion of this circuit, the energizing coil 102 is energized to move switch arms 104, 105 and 106 into engagement with contacts 107, 108 and 109 respectively. Upon the engagement of switch arm 104 with contact 107, a holding circuit is completed from the secondary 114 of step-down transformer 113 through wire 119, wire 121, switch arm 104, contact 107, energizing coil 102 and wire 115 back to the secondary 114. This holding circuit maintains the energizing coil 102 energized to maintain the switches in engagement with their respective contacts even though the contact 93 of the room thermostat 91 is moved out of engagement with the contact 94.

Upon a rise in temperature above a predetermined value, thermostat 91 moves the contact 93 into engagement with the contact 95 thereby completing a neutralizing or bucking circuit from the secondary 114 of step-down transformer 113 through wire 119, wire 121, switch arm 104, contact 107, wire 120, binding post 92, thermostat 91, contacts 93 and 95, wire 97, switch arm 99, contact 101, wire 117, bucking coil 103, wire 116 and wire 115 back to the secondary 114. Upon completion of this bucking or neutralizing circuit, the bucking coil 103 of the relay is energized to neutralize the pulling effect of energizing coil 102 whereby the biasing means moves the switch arms 104, 105 and 106 out of engagement with the contacts 107, 108 and 109.

When the switch arms 98 and 99 are moved into engagement respectively with the contacts 101 and 100 for summer cooling operation, the exact reverse action is accomplished. Upon a rise in temperature of the room above a predetermined value, the thermostat 91 moves the contact 93 into engagement with contact 95 to complete a circuit through the contact 100 of the reversing switch to cause energization of the energizing coil 102 of the relay to cause closing of switches 104, 105 and 106 with respect to the contacts 107, 108 and 109. By movement of switch arm 104 into engagement with the contact 107, a holding circuit is completed for the coil 102 of the relay as above. Upon a decrease in temperature below a predetermined value, the contact 93 is moved into engagement with contact 94 by the thermostat 91 to complete a circuit through the contact 101 of the reversing switch to cause energization of the bucking or neutralizing coil 103 which neutralizes the pulling effect of the energizing coil 102 which allows opening of the switches 104, 105 and 106 with respect to their contacts 107, 108 and 109 by means of the biasing means.

Connected to the line wire 111 is a wire 123 which is in turn connected to two wires 124 and 125. The wire 124 is connected to the contact 108 and the wire 125 is connected to the contact 109. The switch arm 105 which cooperates with the contact 108 is connected by means of a wire 126 and the wire 87 to the motor 44 which controls the operation of the circulating pump 37. The motor 44 of the circulating pump 37 is connected 75 by means of the wire 88, a wire 127, a wire 128

and a wire 129 to the line wire 110. The switch arm 106 which cooperates with the contact 109 is connected by means of a wire 130 to the motor 51 which operates the fan 49 of the air conditioning unit 45 and the motor 51 is in turn connected by a wire 131, the wire 128 and the wire 129 to the line wire 110. 5

When the switch arms 105 and 106 are moved into engagement with the contacts 108 and 109, an electric circuit is completed from the line 10 wire 111 through wire 123, wire 124, contact 108, switch arm 105, wire 126, wire 87, electric motor 44, wire 88, wire 127, wire 128 and wire 129 to the line wire 110 to cause energization of the electric motor 44 to cause operation of the circulating 15 pump 37. Another circuit is also completed from the line wire 111, through wire 123, wire 125, contact 109, switch arm 106, wire 130, electric motor 51, wire 131, wire 128 and wire 129 to the line wire 110 to cause energization of the electric 20 motor 51 to cause operation of the fan 49 of the air conditioning unit 45.

From the above it is seen that for winter operation when the thermostat calls for heat to move the contact 93 into engagement with the 25 contact 94, the circulating pump 37 is operated to cause circulation of the heating fluid through the heat exchanger 46 and the electric motor 51 will be energized to cause operation of the fan 49 to force air over the heat exchanger 46 and deliver this heated air to the rooms C and D to cause heating thereof. When the temperature rises above a predetermined value so as to move contact 93 into engagement with contact 95, the motor 44 is deenergized to cause stopping of the 30 circulating pump 37 and the motor 51 is deenergized to cause stopping of operation of the fan 49 whereby heating fluid is not supplied to the heat exchanger 46 and whereby air is not passed over the heat exchanger 46 or delivered to the 35 rooms C and D. For summer operation, when the temperature of the room C is above a predetermined value, contact 93 of the thermostat 91 is moved into engagement with the contact 95 to move switch arms 104, 105 and 106 into engagement with the contacts 107, 108 and 109 to cause 40 operation of the circulating pump 37 and the fan 49 of the air conditioning unit 45 to deliver cooled air to the rooms C and D to lower the temperature thereof. When the temperature in 45 the room C falls below a predetermined value, the contact 93 of the thermostat 91 is moved into engagement with the contact 94 to move the switch arms 104, 105 and 106 out of engagement with the contacts 107, 108 and 109 respectively to 50 stop operation of the circulating pump 37 and the fan 49 to stop delivery of the cooled air to the rooms C and D. 55

Located in the room C is a humidity responsive device 133 of usual design, containing a switch 60 which is moved to closed position when the relative humidity of the room decreases below a predetermined value and which is moved to open position when the relative humidity of the room increases above a predetermined value. The 65 humidity responsive device 133 is connected to the switch arm 106 by means of a wire 134 and the humidity responsive device 133 is also connected by means of a wire 135 to the motor device or solenoid 57. The solenoid 57 is also connected by 70 means of a wire 136 to a contact 137. Cooperating with the contact 137 is a manually operated switch arm 138 which is connected by means of a wire 139 to the connection of wires 129 and 128.

When the parts are adjusted for winter operation, the switch arm 138 is moved into engagement with contact 137 and when the room thermostat calls for heat so as to move switch arm 106 into engagement with contact 109 and when the relative humidity of the room C is below a predetermined value, a circuit is completed from the line wire 111 through wire 123, wire 125, contact 109, switch arm 106, wire 134, humidity responsive device 133, wire 135, solenoid 57, wire 136, contact 137, switch arm 138, wire 139 and wire 129 to the line wire 110. Completion of the above circuit causes energization of the solenoid 57 which causes opening of the valve 56 to admit water to the humidifying spray device 55 to add water vapor to the heated air delivered to the rooms C and D. If the relative humidity of the room rises above a predetermined value, the humidity responsive device 133 opens the above circuit to cause deenergization of the solenoid 57 to close the valve 56 to stop operation of the humidifying spray device 55. Also, if the temperature in the room C rises above a predetermined amount so as to move switch arm 106 out of engagement with contact 109, the above circuit is broken to cause deenergization of solenoid 57 to close the valve 56 to stop operation of the humidifying spray 55.

Since it is not advisable to add water vapor to the air delivered to the rooms C and D for summer or cooling operation, the switch arm 138 is moved out of engagement with the contact 137 to prevent operation of the humidifying spray device 55 during summer operation.

Briefly, the operation of the device for winter or heating operation is as follows: when the temperature of the room A lowers below a predetermined value, the control valve 29 is opened and the circulating pump is placed in operation to cause circulation of the heating fluid through the radiators 32 in rooms A and B to cause heating thereof by direct radiation regardless of temperature or humidity conditions existing in rooms C and D. Upon a rise in temperature in room A above a predetermined amount, the control valve 29 is closed and the circulating pump 37 is stopped to prevent circulation of the heating fluid through the radiators 32 of rooms A and B. When the temperature in the room C lowers below a predetermined value, circulating pump 37 is placed in operation to cause circulation of heating fluid through heat exchanger 46 and the fan 49 is placed in operation to pass air over the heat exchanger 46 into the rooms C and D regardless of temperature conditions existing in rooms A and B. If the relative humidity in the room C is less than a predetermined value, the humidifying spray device 55 is placed in operation to add water vapor to the heated air delivered to the rooms C and D to increase the relative humidity thereof. When the temperature in the room C rises above a predetermined value, the circulating pump 37 is stopped to prevent circulation of the heating fluid through the heat exchanger 46, the fan 49 is stopped to prevent delivery of air to the rooms C and D and the adding of water vapor to the air by means of the humidifying spray device 55 is prevented. Further, if the relative humidity in the room C rises above a predetermined value, the humidifying spray device 55 is placed out of operation even though heated air may be supplied to the rooms C and D by the fan 49.

From the above, it is seen that the control valve 29 is controlled solely by the room thermostat 60 of room A and that the fan 49 is controlled only

by the room thermostat 91 of the room C and that circulating pump 37 is controlled either by the room thermostat 60 of room A or the room thermostat 91 of room C. By reason of these independent and related control systems, it is possible to maintain the temperature of the rooms A and B at any value regardless of the temperature existing in rooms C and D and vice versa and it is also possible to maintain the relative humidity in the rooms C and D at a certain value regardless of the relative humidity existing in the rooms A and B.

A brief description of the summer operation of the air conditioning system is as follows: when the temperature in room A rises above a predetermined value, the control valve 29 is opened and the circulating pump 37 is placed in operation to cause circulation of cooling fluid through the radiators 32 of rooms A and B to cause cooling of these rooms by direct radiation regardless of the condition existing in the rooms C and D and when the temperature of the room A falls below a predetermined value, the control valve 29 is closed to prevent circulation of the cooling fluid through the radiators 32. When the temperature in room C rises above a predetermined value, the circulating pump 37 is placed in operation to cause circulation of the cooling fluid through the heat exchanger 46 and the fan 49 is placed in operation to pass air over the heat exchanger 46 to deliver cooled air to the rooms C and D. Upon a decrease in temperature, in room C below a predetermined value the fan 49 is deenergized to stop the flow of cool air to the rooms C and D. Since the switch 138 is moved out of engagement with the contact 137 during summer or cooling operation, the humidifying spray 55 is rendered inoperative by the manually operated switch arm 138.

From the above, it is seen that I have invented an automatic zone air conditioning system 40 wherein a room or group of rooms may be conditioned to a different degree than another room or another group of rooms and that provision is made for winter operation and for summer operation and all that is necessary to convert the 45 system from winter operation to summer operation is the throwing of two reversing switches and the manual resetting of the four shut-off valves.

Various modifications may be made in the system embodying my invention without departing 50 from the spirit and scope thereof and I desire therefore that only such limitations shall be placed thereon as are imposed by the prior art or set forth in the appended claims.

I claim as my invention:

1. In a system of the class described for conditioning a plurality of rooms, a source of conditioning fluid, heat exchanger means for certain of said rooms, other heat exchanger means for other of said rooms, conducting means between 60 said source and said first heat exchanger means and between said source and said other heat exchanger means, a condition responsive device in certain of said rooms, another condition responsive device in other of said rooms, and means under the command of one of said condition responsive devices for causing circulation of conditioning fluid through said heat exchanger means for all of said rooms and under the command of the other condition responsive device for causing 70 circulation of conditioning fluid through said heat exchanger means for said other of said rooms.

2. In a system of the class described for conditioning a plurality of rooms, a source of con- 75

ditioning fluid, heat exchanger means in certain 5 of said rooms for directly conditioning said rooms, means connecting said source of conditioning fluid and said heat exchanger means, an air conditioning unit for indirectly conditioning other of said rooms comprising a heat exchanger mechanism and air circulating means, means connecting said source of conditioning fluid and the heat exchanger mechanism of said air conditioning 10 unit, a condition responsive device in said certain of said rooms, and means under the command of said condition responsive device for causing circulation of conditioning fluid through said heat exchanger means and the heat exchanger mechanism of said air conditioning unit.

3. In a system of the class described for conditioning a plurality of rooms, a source of conditioning fluid, heat exchanger means in certain 20 of said rooms for directly conditioning said rooms, means connecting said source of conditioning fluid and said heat exchanger means, an air conditioning unit for indirectly conditioning other of said rooms comprising a heat exchanger mechanism and air circulating means, 25 means connecting said source of conditioning fluid and the heat exchanger mechanism of said air conditioning unit, a condition responsive device in said certain of said rooms, another condition responsive device in said other of said rooms, and means under the command of one 30 of said condition responsive devices for causing circulation of conditioning fluid through said heat exchanger means and the heat exchanger mechanism of said air conditioning unit and 35 under the command of the other condition responsive device for causing circulation of conditioning fluid through the heat exchanger mechanism of said air conditioning unit and operation of the air circulating means.

4. In a system of the class described for conditioning a plurality of rooms, a source of conditioning fluid, heat exchanger means for certain 40 of said rooms, conducting means between said source and said heat exchanger means, a control device in said conducting means, other heat exchanger means for other of said rooms, conducting means between said source and said other heat exchanger means, a condition responsive device in said certain of said rooms, a condition 45 responsive device in said other of said rooms, circulating means for circulating conditioning fluid through said conducting means, means responsive to one of said condition responsive devices and associated with said control device and said circulating means for circulating conditioning fluid through said heat exchangers for all 50 of said rooms, and means responsive to the other of said condition responsive devices and associated with said circulating means for circulating fluid through said heat exchangers for said 55 other of said rooms.

5. In a system of the class described for conditioning a plurality of rooms, a source of conditioning fluid, heat exchanger means in certain 60 of said rooms for directly conditioning said rooms, conditioning fluid conducting means between said source and said heat exchanger means, a control device in said conditioning fluid conducting means, an air conditioning unit for indirectly conditioning other of said rooms comprising a heat exchanger mechanism and air circulating means, conditioning fluid conducting means between said source and the heat exchanger mechanism of said air conditioning unit, 65 a condition responsive device in said certain of

said rooms, a condition responsive device in said other of said rooms, circulating means for circulating conditioning fluid through said conditioning fluid conducting means, means associated with one of said condition responsive devices, 5 said control device and said circulating means for circulating conditioning fluid through said heat exchangers and the heat exchanger mechanism of said air conditioning unit, and means associated with the other condition responsive 10 device and said circulating means for causing circulation of heating fluid through the heat exchanger mechanism of said air conditioning unit.

6. In a system of the class described for conditioning a plurality of rooms, a source of conditioning fluid, heat exchanger means in certain 15 of said rooms, conditioning fluid conducting means between said source and said heat exchanger means, a control device in said conditioning fluid conducting means, an air conditioning unit for other of said rooms comprising a heat exchanger and an air circulating means for delivering conditioned air to said other rooms, 20 conditioning fluid conducting means between said source and said heat exchanger of said air conditioning unit, a condition responsive device in said certain of said rooms, another condition responsive device in said other of said rooms, circulating means for circulating conditioning 25 fluid through said conditioning fluid conducting means, means operatively connected to one of said condition responsive devices, said control device and said circulating means for circulating conditioning fluid through said heat exchanger means for conditioning said certain of said rooms, and means operatively connected to said other condition responsive device, said circulating means and said air circulating means for causing circulation of conditioning fluid 30 through said heat exchanger of said air conditioner and to cause delivery of conditioned air 35 to said other of said rooms.

7. In a system of the class described for conditioning a plurality of rooms, heat exchanger 45 means for certain of said rooms, a control device for said heat exchanger means, an air conditioning unit for other of said rooms comprising a heat exchanger and a fan, circulating means for circulating heating fluid through said heat exchanger means and through said heat 50 exchanger of said air conditioning unit, a thermostat in certain of said rooms associated with said control device and said circulating means responsive to a decrease in temperature to cause circulation of heating fluid through said heat exchanger means, a thermostat in other of said rooms associated with said circulating means and said fan and responsive to a decrease in temperature to cause circulation of heating fluid 55 through said heat exchanger and to pass air over said heat exchanger whereby said other rooms are heated, means for stopping the supply of heating fluid and for supplying cooling fluid to said heat exchanger means and said heat exchanger of said air conditioning unit, and means 60 for reversing the action of said thermostats when cooling fluid is supplied to said heat exchanger means and said heat exchanger of said air conditioning unit.

8. In a system of the class described for conditioning a plurality of rooms, radiators for certain of said rooms, a control device for said radiators, an air conditioning unit for other of said rooms comprising a heat exchanger, a fan 65

- and humidifying means, a humidity responsive device in the other of said rooms for controlling the operation of said humidifying means, circulating means for circulating heating fluid 5 through said radiators and said heat exchanger, a thermostat in certain of said rooms responsive to a decrease in temperature to operate said control device and said circulating means to circulate heating fluid through said radiators to 10 heat the certain of said rooms, a thermostat in the other of said rooms responsive to a decrease in temperature to condition said humidity responsive device for operation and to operate said circulating means and said fan to circulate heating fluid through said heat exchanger and to 15 pass air over said heat exchanger to the other of said rooms, means for stopping the supply of heating fluid and for supplying cooling fluid to said radiators and said heat exchanger, and 20 means for reversing the action of said thermostats when cooling fluid is supplied to said radiators and said heat exchanger of said air conditioning unit.
9. In a system of the class described for conditioning a plurality of rooms, radiators for certain of said rooms, a control device for said radiators, an air conditioning unit for other of said rooms comprising a heat exchanger, a fan and humidifying means, a humidity responsive 25 device in the other of said rooms for controlling the operation of said humidifying means, circulating means for circulating heating fluid through said radiators and said heat exchanger, a thermostat in certain of said rooms responsive to a decrease in temperature to operate said control device and said circulating means to circulate heating fluid through said radiators to heat the certain of said rooms, a thermostat in the other of said rooms responsive to a decrease 30 in temperature to condition said humidity responsive device for operation and to operate said circulating means and said fan to circulate heating fluid through said heat exchanger and to pass air over said heat exchanger to the other of said rooms, means for stopping the supply of heating fluid and for supplying cooling fluid to said radiators and said heat exchanger, and 35 means for reversing the action of said thermostats when cooling fluid is supplied to said radiators and said heat exchanger of said air conditioning unit.
10. In a system of the class described for conditioning a plurality of rooms, heat exchanger 5 means for certain of said rooms, an air conditioning unit for other of said rooms comprising a heat exchanger and a fan, means for controlling the circulation of heating fluid through said heat exchanger means and through said 10 heat exchanger of said air conditioning unit, a thermostat in certain of said rooms associated with said circulation controlling means responsive to a decrease in temperature to cause circulation of heating fluid through said heat exchanger means, a thermostat in other of said rooms associated with said circulation controlling means and said fan and responsive to a decrease in temperature to cause circulation of 15 heating fluid through said heat exchanger and to pass air over said heat exchanger whereby said other rooms are heated, means for stopping the supply of heating fluid and for supplying cooling fluid to said heat exchanger means and said heat exchanger of said air conditioning unit, 20 and means for reversing the action of said thermostats when cooling fluid is supplied to said heat exchanger means and said heat exchanger of said air conditioning unit.
11. In a system of the class described for conditioning a plurality of rooms, first heat exchanger means for certain of said rooms, a second heat exchanger means for other of said rooms, circulation controlling means for controlling the circulation of heating fluid through 35 said heat exchanger means, a thermostat responsive to a decrease in temperature in said certain rooms for controlling said circulation controlling means to increase the circulation of heating fluid through said first heat exchanger 40 means, a thermostat responsive to a decrease in temperature in the other rooms for controlling said circulation controlling means to increase the circulation of heating fluid through said second heat exchanger means, means for stopping the supply of heating fluid and for supplying cooling fluid to said heat exchanger means, and means for reversing the action of said thermostats when cooling fluid is supplied. 45

ARTHUR C. GRANT.
